LIVE COAL SPREADER FOR UNDERFEED TYPE OF STOKER FURNACES

Thomas W. Faull, Dunkirk, Ind.

Application December 31, 1948, Serial No. 68,459

1 Claim. (Cl. 110—44)

1

This invention relates to improvements in stoker fed furnaces.

Whereas in the operation of a furnace of above description wherein the fuel is fed upwardly, as by a conventional automatic underfeed stoker, advantages have been accomplished by controlling the delivery of coal to the retort, and by regulating of the air draft that is admitted into the combustion chamber of the furnace, there is still to be contended with the problem of how best to keep the fire clean. That is to say, how best to minimize the obstructive effects which are incident to the formation of clinkers.

A cause of uneven distribution of fuel, and of clinkering which has presented a most difficult problem, is that wherein a fusing takes place in the median portion of the fuel retort and burner thereby resulting in a cone or coke tree which rises to a relatively high plane above the fire bed whence it topples. The tumbled down mass so imposed upon the fire bed forms a clinker deposit which not only obstructs combustion, but interferes with stoker control. Said deposit also involves considerable inconvenience and the expenditure of special labor in the removal of same.

It is with the above phase of clinkering that my invention is concerned, and the object, broadly stated, is to provide an appliance adapted to be positioned within the confines of the combustion chamber of the furnace, and to so function in combination with and in relation to the stoker, that the coke cone in its rise, is stopped before it will become enlarged and fused, and whereby the mass so stopped, will be disintegrated and the fragmentary portions thereof caused to subside and to be dispersed in the fire bed.

The said object, together with certain specific aims as will presently appear, are accomplished by, and my invention is embodied in the new construction, combination and arrangement of parts illustrated in the accompanying drawings and described in the following specification.

The several parts of the invention, as they appear in the different views in the drawings are identified by suitable characters of reference applied to them.

In the drawings:

Figure 1 is a top plan view of my new appliance.

Figure 2 is a side view of the device the base portion thereof being shown in cross section on section line and in the direction of arrows 2—2 in Figure 1.

Figure 3 is a top plan view, taken on the section line and in the direction of arrows 3—3 in Figure 2.

Figure 4 is a side view of a furnace and underfeed stoker connections, portions of the furnace casing being broken away, and a portion of the furnace structure proper being shown in cross section, and my new appliance being shown as it appears in operative position.

2

Figure 5 is a top plan view, taken on the section line and in the direction of arrows 5—5 in Figure 4.

In a furnace of the typical form and structure indicated in the drawing, the upper portion 11 of the cylindrical body of the furnace forms a combustion chamber, and the lower portion 14 of said body forms the fire pot. Conduit 15, rectangular in cross section extends from said combustion chamber and through the casing 16 of the furnace body, and is closed by a conventional inspection door 18.

The fuel, as semi-pulverized coal, is fed by means of a stoker which includes coal tube 19, worm 20, upwardly directed retort 21, and annular burner 22, through which said burner, air for supporting combustion is admitted through air duct 23. In the space 24 within the confines of the casing 16, is circulation of heat conveying air. The coal propelled by the worm moves upwardly into the retort and the burner whence it reaches the hot coke or live fire bed 26. To maintain proper depth and condition of the fire bed, the power transmission device (not shown) which actuates the worm; and the blower mechanisms (not shown) which provides air flow through duct 23, are capable of being controlled and regulated according to the heating requirements, it being essential that a constant draft over the fire be had.

As a consequence of any failure of supervisory control and adjustment of the stoker coal feed and the stoker air flow to meet changing conditions which are incident to varying heating requirements and to varying qualities and consistencies of the fuel used, there occurs a passing of air currents up alongside the cylindrical central zone of the fuel mass. Resultant from the action of said currents is the fusion of the median or central portion of the fuel into a mass which rises in a cohesive cone or tree-like formation called a coke tree. It gradually rises high in the combustion chamber, becomes clinkered in consistency and finally topples, thus becoming imposed on the fire bed and causing such obstruction to combustion that the fire bed is rendered inefficient and subject to be restored to normal condition.

The rendition of the fire bed into the above named inefficient condition, augments the amount of care already existent and necessary in the breaking up and distributing of usual clinkers, and it brings on the additional necessity of the manual breaking up and removing the clinkered mass which will have formed as aforesaid. Said condition is accompanied of course by interruption of the heating service, and in many instances is accompanied by such an abnormal condition in the fire bed, that in order to get said fire bed restored to normal and proper burning conditions, a complete removal of ashes and clinkers is necessitated, as is also required new adjustment of coal feed and of air flow.

My new appliance for minimizing the adverse effects which are incident to coke tree formations, in the typical representation here presented, is of size, general proportions and detail suitable for a conventional furnace intended for residential heating.

A base member consists of a flat bar 31 having an upward bend and thence a parallel bend which forms a head piece 32. An upright pivot pin 33 integrated with said base member projects upwardly beyond the plane of the top of said head piece 32 and it is provided with a transverse hole 34. At a location spaced from said pivot pin is a concentric aperture 35 of length indicated in Figure 3. Hole 36 in said base member will presently be referred to.

A reach arm 37, arched in formation, made of resilient steel bar metal has its one end portion secured as by a bolt 38 and nut 39 to the top side of a metal disk 40. The other and downwardly directed part of said bar is turned at a right angle to form a foot piece 41. Provided in said foot piece is a vertical bore 42 through which the pivot pin 33 is received. Integrated with and extending downwardly from the end portion of said foot piece is a stud 43.

A disk 45 made of refractory material, as fire clay, is of diameter approximately one third of the diameter of the combustion chamber of the furnace, and is of substantial thickness. It is secured, as by imbedded bolts 46 (one only of which said bolts 46 is shown) to said metal disk 40. The said base member is combined with the foot piece 41 of the said reach arm 37 by placing said reach arm with its foot-piece in engagement with the top surface of the head piece 32 of the said base member, the pivot pin 33 being received in bore 42, and the stud 43 being received in the arcuate aperture 35. Upon placing a washer 47 on the pivot pin, and then disposing a cotter pin 48 through the hole 34, the device is complete.

Installing the device in readiness for use consists in providing two threaded holes in a side of the floor portion 17 of the conduit 15 of the furnace; then inserting the device through said conduit and disposing it in upright position and then securing the base member to the floor of the conduit, as by cap screws 50. The reach arm is then swung on its pivot 33 to the point where the disk 45 is in position above the central area of the fire bed, and at a plane a distance above said fire bed equal to about one half the diameter of the burner 22. The distance through which said reach arm may be swung is limited by the stud 43 coming to engagement with an end of the arcuate aperture 35.

The stoker having been started and the fire bed having been established, the user now with the poker (not shown), a usual accessory for stoker fed furnaces, inserted through the conduit 15 and disposed against a side of the reach arm 37, swings said arm to position wherein the refractory plate or disk 45 is at central position above the fire bed, as indicated in Figure 5.

Whereas the refractory disk 45 so poised does not hinder combustion, it functions as a deflector or abutment device in such manner that when for any reason, as by occurrence of derangement of coordination of fuel feed and air flow regulation, a coke mass as hereinbefore referred to rises, the said mass, in its rise (as indicated by the broken lines in Figure 4), becomes impinged against the bottom of said refractory disk and is thereby arrested.

Incident to the upward pressure which is exerted against said disk is a reaction by the resilient reach arm. By this arrest or stopping of the rise of said mass, and by the reaction of said reach arm, the said mass is caused to be disintegrated. In the disintegrating so caused, the disjoined chunk like portions are caused to be dispersed in broken and separated manner upon the fire bed. Thus tendency to clinkering is minimized and impairment of combustion is avoided. The said refractory disk also functions to arrest the ascent of fly ash and to disperse same in the central zone above the fire bed.

The said reach arm, capable, as it is, of being swung to position at one side or the other of the combustion chamber, does not interfere with the usual use of the poker in the transaction of removing clinkers from the fire bed and fuel mass and for working around the outer portion of the burner, and which said working is a usual procedure in the conditioning of the furnace.

The reach arm extending upwardly, as it does, and being arched as shown, besides having the inherent and desired characteristic of strength and resiliency, is of form and position to so withstand the combustion chamber temperature, as to be durable and dependable under all conditions of firing.

The appliance is economical of manufacture, dependable, and easy to handle and to install. Its use is readily understood and practiced.

Whereas I have shown my invention in what I consider its preferred form and structure in detail, it will be understood that minor changes and modifications may be made without departing from the spirit and principle of my invention or sacrificing any of its advantages.

What I claim as my invention is:

An attachment adaptable for use in connection with the combustion chamber structure of an underfed furnace, consisting of a flat bar having an upward and thence parallel bend, which said bend forms a head piece, there being a vertical hole through said head piece and an arcuate slot concentric to the said hole, and the base portion of said bar being adapted to be secured to an inner portion of said chamber structure and near the inspection conduit thereof, an upright pivot pin secured to said bar and having its upper end projecting through the hole of and beyond the plane of the top of said head piece, and provided with a diametric hole extending therethrough, an upright resilient reach arm arched at its upper portion, said arm at its lower portion having a right angle bend to form a foot piece, there being a vertical hole in said foot piece and in which said hole the aforesaid pivot pin is received, said foot piece having a downwardly directed stud which is received in the aforesaid arcuate slot, a cotter pin installed in the hole of said pivot pin, and a disk like plate of refractory material secured to the downwardly directed free end of the said reach arm.
